UNITED STATES PATENT OFFICE.

SAMUEL RANKIN AND CHARLES E. STORM, OF STRASBURG, ILLINOIS.

BALING-PRESS.

SPECIFICATION forming part of Letters Patent No. 623,826, dated April 25, 1899.

Application filed August 18, 1898. Serial No. 688,919. (No model.)

To all whom it may concern:

Be it known that we, SAMUEL RANKIN and CHARLES E. STORM, citizens of the United States, residing at Strasburg, in the county of

5 Shelby and State of Illinois, have invented certain new and useful Improvements in Baling-Presses; and we do hereby declare the following to be a full, clear, and exact description of the invention, such as will enable others skilled in the art to which it appertains to make and use the same.

This invention relates to improvements in baling presses or machines of that class embodying mechanism for automatically compressing hay, straw, and materials of like character into the form of bales and for applying binding cords or wires around the material while in a state of compression.

The objects of the invention are, first, to provide a machine of this character having improved mechanism whereby the several successive operations of feeding, compressing, binding, and delivering the material in the form of bales may be rapidly, conveniently, and effectually performed and chocking of the material in the hopper and irregularities in the feed prevented; second, to provide simple and effective packing devices for receiving the material from the feeding-fork and forcing the same into the baling-chamber; third, to provide an improved form of needle and coacting devices for threading the binding cords or wires with certainty at the proper intervals; fourth, to provide novel automatic clamping means for holding the free ends of the binding cords or wires while they are being twisted and tied; fifth, to provide an improved and efficient construction of mechanism for twisting and cutting the binding-wires; sixth, to provide simple and positive mechanism for imparting motion to the various operative parts of the apparatus and intermittent mechanism for throwing the wire-threading needles and twisting and cutting mechanism into and out of operation, and, finally, to generally simplify and improve the construction and render more efficient and certain the operation of this class of apparatus generally.

5c To these ends the invention consists in the features and in the construction, combination, and arrangement of parts hereinafter

more fully described and specifically set forth in the appended claims, reference being had to the accompanying drawings, forming a 55 part of this specification, wherein—

Figure 1 is a side elevation of a baling-machine constructed in accordance with our invention. Fig. 2 is a detail perspective view of the rotating toothed segment and clutch. 60 Fig. 3 is a top plan view of the machine. Fig. 4 is a diagrammatic view illustrating the manner in which the binding-wire is threaded by the needle and looped about the bale and its free ends tied by the twister. Fig. 5 is a rear 65 elevational view of the machine. Fig. 6 is a detail perspective view of one of the packers. Fig. 6^a is a longitudinal section thereof, illustrating the movements of the parts in dotted lines. Fig. 7 is a vertical longitudinal sec- 70 tion of the machine. Fig. 8 is a detail perspective view of the trip-lever. Fig. 9 is a sectional plan view of the machine, taken on the line 9 9 of Fig. 1. Fig. 10 is a detail view of the binding-wire clamps and connecting parts. Fig. 11 is a cross-section 75 through the machine on line 11 11 of Fig. 9. Fig. 12 is a fragmentary perspective view of the wire twisting and cutting mechanism. Fig. 13 is a detail sectional view through a 80 portion of the frame and one of the cam-gears of same, showing the spring-pressed stop-roller. Figs. 14 and 15 are perspective views of the wire cutting and twisting jaws. Fig. 16 is a broken detail sectional view showing 85 the sliding bearing-block which acts upon the pivoted cutting and twisting jaw. Fig. 17 is a diagrammatic view showing the preliminary step in the threading of the binding-wire. Fig. 18 is a similar view showing the 90 second step, in which the needle is about to complete the formation of the loop. Fig. 19 is a perspective view illustrating the arrangement of the features shown in Fig. 4. Fig. 20 is a similar view showing the ends of the 95 wires twisted. Fig. 21 is a diagrammatic perspective view showing the manner in which the binding-wires are held by the clamping-irons 67 and 70 while being twisted and cut.

100 Referring now more particularly to the drawings, wherein like numerals of reference designate corresponding parts throughout the several views, 1 represents the main frame

of the machine, which is oblong and rectangular in form and comprises in its construction two longitudinal side sills 2, two upper longitudinal supporting-bars 3, mounted on 5 posts 4, rising from said sills, and upper and lower cross-pieces 5 and 6, respectively connecting the sills and supporting-bars. This particular construction of frame, while deemed preferable, is not essential and may 10 be altered to suit varying conditions, and, if desired, said frame may also be mounted on wheels, so as to permit of the machine being transported from place to place to work in a field or alongside a thresher.

15 The baling or compression chamber 7 extends from the center of the frame to the rear or delivery end thereof and is open at both ends and formed by a bottom 8, sides 9, and a top 10, said sides being provided at the 20 mouth of the chamber with longitudinal slots or openings 11 for passage of the needles, by which the binding-wires are threaded across said chamber in the manner hereinafter described. Mounted upon the supporting-bars 25 3 at the front or opposite end of the frame is a feed chamber or hopper 12, open at its rear end and provided with a curved bottom 8^a, which preferably forms, as shown, an extension of the bottom of the compression-chamber. The hopper is divided centrally to form 30 a feed-chamber proper, 13, at its front end and an open compartment 14 in rear thereof by spaced guide-strips 15, which are curved and extended rearwardly at their lower ends 35 and connected to the top of the baling-chamber or to the intermediate cross-piece 6 above the mouth thereof.

40 Mounted transversely at the rear or open end of the compartment 14 is a power-shaft 16, having a central crank arm or portion 17 and carrying at one end a belt-wheel 18, adapted to receive power from a threshing-machine or suitable motor, and at each end a bevel-pinion 19 19^a. A feeding-fork 20 is 45 provided with a head 21, loosely mounted on the crank portion of the power-shaft, a series of prongs or tines 22, which project through the guides 15, and an arm 23, which works loosely in an opening in an oscillatory bearing-block 24, mounted in rear of the hopper and by which the fork is guided in its travel. In operation as the power-shaft revolves in the direction of the arrow, Fig. 3, the fork turns therewith, and the tines thereof travel 55 in the arc of a circle through the hopper and carry the hay or straw to the mouth of the baling-chamber, and then the fork moves upward in a direct vertical line to withdraw the tines from engagement with the straw. During 60 this operation the arm of the fork moves freely through the oscillatory block, and the latter turns on its axis to compensate for and to enable the fork to traverse its irregular path with ease and without binding.

65 Arranged above the baling-chamber and on opposite sides thereof are parallel shafts 25 and 25^a, carrying at their inner ends bevel-

70 gears 27, which mesh with the bevel-pinnions 19 and 19^a on the power-shaft. These shafts also carry at their outer ends bevel gear-wheels 28, which mesh with like gear-wheels 29 on the upper ends of vertical crank-shafts 30, journaled in side extensions of the frame and located on opposite sides of the baling-chamber at the delivery end thereof. Said 75 shafts operate the packers which force the straw fed by the feed-fork into the baling-chamber and compress the same therein. Each packing device consists of a longitudinal carrier 31, mounted to reciprocate in 80 guides on the side of the baling-chamber, which carrier is provided with upper and lower flanges 31^a to receive the inner ends of a right-angularly-reciprocating arm 32 and connecting-rod 33, which are pivoted thereto 85 near their inner ends and jointed at said ends to each other. The outer or free end of the arm carries a packing-finger 34, that is adapted to move through a guide-opening in the inner end of the carrier and projects through one of 90 the openings 11 into the mouth of the baling-chamber, while the outer end of the connecting-rod is journaled upon the crank portion of the shaft 30. When this shaft turns, the carrier is reciprocated back and forth longitudinally 95 of the baling-chamber, and at the same time the packing-finger 34 is reciprocated transversely, so as to move into and out of the mouth of said chamber. This operation will be readily understood by reference to Figs. 6, 6^a, and 9 of the drawings, from which it will be seen that when the arm 32 and rods 33 are in longitudinal alinement, which position they assume when the crank portion of the shaft 30 moves closest to the baling-chamber in making 100 one half of a revolution, the packing-finger projects to its fullest extent within the mouth of the baling-chamber and the carrier is being reciprocated toward the delivery end of said chamber, and that, on the contrary, 105 when the crank portion of said shaft moves outwardly from the baling-chamber in making the other half of its revolution the carrier is reciprocated in the reverse direction, or toward the mouth of the baling-chamber, and the free end of the connecting-rod drawn outwardly, whereby the inner end of the arm is forced inwardly toward the chamber and the outer end thereof away from the chamber to withdraw the packing-finger, as indicated by 110 broken lines in Fig. 6^a. The operation of the packers is so timed with respect to that of the feeding-fork that when the fork moves through the hopper to force the straw toward the baling-chamber the carrier moves inwardly and the beating-finger outwardly, as 115 shown by broken lines in Figs. 6^a and 9, thus allowing the fork to move freely into the mouth of said chamber. When, however, the fork begins to move upwardly, as before described, the carrier is reciprocated in the reverse direction and the beating-finger projected into the mouth of the baling-chamber, 120 so that as the next feeding movement of the 125 130

fork commences the fingers will force the hay or straw previously fed into the chamber, and this operation is continued until a sufficient amount of straw is compacted therein to form a bale, whereupon the tie-wire threading, twisting, and cutting mechanism is automatically thrown into operation, as hereinafter described. For the purpose of preventing rebounding of the straw a pair of spring-actuated dogs or hooks 35 are provided on each side of the mouth of the baling-chamber. These hooks are adapted to be forced back out of the way to allow the straw to enter the chamber and then spring back into their normal positions to retain the straw therein.

Located at one side of the machine is a wire-threader consisting of a frame 36, formed of a pair of arms or bars 37, arranged one above the other and pivoted at their inner ends to 20 the frame near the crank-shaft 30 to swing in a direction transversely to the baling-chamber, said arms being provided with longitudinal slots 38, in which the cranked portions of a double-crank shaft 39 are fitted to slide. 25 The outer ends of these arms are connected by a head 40, carrying a pair of inwardly-projecting needles 41, provided at their free ends with eyes 42 for passage of the binding-wires, which feed through guides 42^a from 30 reels (not shown) mounted alongside the machine. These needles are adapted to move through the openings 11 to thread the tie-wires across the mouth of the baling-chamber both before and after the formation of 35 a bale, and simple and effective automatic mechanism is provided for positively effecting this operation. Mounted upon the upper end of the shaft 39 is a bevel-pinion 43, which is adapted to mesh with a rotating segment 44, carried by an arbor 45, loosely mounted on the side shaft 25 and provided with a clutch-head 46. This segment is of peculiar construction, being provided with peripheral spur-teeth 44^a, which are extended 40 on one side thereof to form bevel-teeth 44^b. Pivoted to said segment is a pawl 47, having a lug or tongue 48, adapted to engage a notch 49 in said clutch-head to rigidly connect the segment thereto, so that it will turn with the 45 shaft. The pawl is normally held in engagement by a ribbon-spring 50. A toothed trip-wheel 51 is rigidly mounted on a revoluble shaft 52 above the baling-chamber, and the lower peripheral portion thereof normally projects thereinto through a slot in the top 10 of said chamber. This shaft 52 carries a striker 53, which when the wheel is revolved is adapted to depress the looped arm 54 on one end of a short transverse rock-shaft 55, which shaft is 50 provided at its other end with an arm 56, normally held in engagement with the pawl 47 by a spring 57 acting on said looped arm to keep the lug or tongue 48 of said pawl from engaging with the clutch-head 46. Normally— 55 that is, when the baling-chamber is being filled—the rotating segment, crank-shaft 39, and the wire-threader frame remain at rest,

the clutch-head 46 alone turning with the shaft; but when the chamber is nearly filled the straw forced thereinto by the packers 70 comes in contact with the toothed wheel and causes the same and its shaft to turn. When the striker 53 depresses the looped arm 56 of the rock-shaft 55, the latter, through an action of spring 50, is operated to withdraw its 75 arm from engagement with the pawl 47, whereupon the latter engages and rigidly connects the rotating segment with the clutch-head turning with shaft 25. As the segment revolves, the beveled tooth portion 44^b thereof meshes with the pinion 43, and the crank-shaft 39 is thereby operated to move the wire-threading needles across the mouth of the baling-chamber and then back again. When the segment completes its revolution, it again 85 comes into contact with the arm 56 and is released from engagement with the clutch by said arm at the same time that the needle is fully reciprocated.

The peculiar manner in which the wire is 90 threaded and clamped will be described more fully hereinafter in connection with the wire twisting and cutting mechanism.

Above the mouth of the baling-chamber is mounted a transverse shaft 58, carrying at 95 its inner end a bevel-pinion 59 and at its outer end a cam 60, having a peripheral groove. The said pinion 59 meshes with a similar pinion 61 on one end of a short counter-shaft 62, extending parallel with the shaft 29, and said counter-shaft carries at its opposite end a spur-pinion 63, which is adapted to mesh with the spur-teeth 44^a on the rotating segment 44, whereby all three shafts 39, 58, and 62 will be operated in quick succession by the 100 segment. Arranged on the opposite side of the frame from the wire-threader is a clamping device consisting of a pivoted bell-crank lever 64, arranged below the cam 60 and having a curved upper vertical arm 65, projecting into the groove of said cam, whereby it is positively connected therewith, a lower vertical arm or extension 66, and a horizontal arm 67, adapted to bear upon the upper side of a division-bar 68, extending between 105 the two intermediate posts 4 on one side of the mouth of the baling-chamber. Pivoted to 110 said bar is a gravity-clamp 69, having a long arm 70, adapted to bear against the under side thereof, and a short arm 71, adapted to be depressed by the said lower arm or extension 66 of the bell-crank lever. These clamping-arms are adapted to be operated simultaneously with the wire-threader frame, and as 115 the needles of said frame thread the upper and lower binding-wires across the frame the peripheral face 60^a of said cam, which is of the greatest distance from the shaft 58, tilts the lever 64, and the arms 67 and 70 are thereby operated to clamp the wires in the 120 manner hereinafter described. As before stated, the needles are operated both preliminarily and subsequently to the packing of the 125 hay or straw in the compression-chamber,

and the wires in addition to being engaged by the clamps are threaded into the jaws of the cutting and twisting mechanism yet to be described. The wires 72 when stretched primarily across the mouth of the baling-chamber are forced backwardly thereinto, and the mass of hay or straw compressed by the packers impinges against said wires, which are thereby drawn outwardly toward the discharge end of said chamber in the form of a loop 73 and caused to embrace the sides and rear end of the bale being formed, the wires freely unwinding from the reels and passing through the eyes of the needles at one side of the machine and the free ends thereof being firmly held by the clamps 67 and 69 at the other side. It will thus be seen that the wires are bound tightly around both sides and the rear end of the straw and assist in its compression, and when the required amount of straw is compressed to form a bale the needles must again be operated to extend the wires across the inner end of the bale and thread new strands across the mouth of the baling-chamber for the reception of the straw compressed to form the succeeding bale. The mechanism for carrying this operation into practical effect has been hereinbefore described, and we will now proceed to describe the mechanism whereby the wires are automatically clamped, twisted, and cut.

Arranged on the same side of the frame as the clamp 64 in transverse alinement with the mouth of the baling-chamber and on the opposite side of the frame from the wire-threading device is a frame 74, composed of the graduated standards or pillows 74^a, 74^b, and 74^c, the two latter having upper and lower cross-bars 74^d and 74^e, respectively. In an arm or bearing projection rising from the intermediate standard 74^b is journaled the extended end 58^a of the shaft 58, and mounted thereon is a spur-gear 75, which is arranged above and communicates motion through the medium of a pinion 75^a to a gear-wheel 75^b, which in turn meshes with a gear-wheel 75^c similar in all respects in construction thereto. These gears 75^b and 75^c operate the upper and lower sets of devices, which cut and twist the free ends of the upper and lower binding-wires, and as said devices are duplicates a description of one will suffice for both. These devices, it may be stated for the sake of brevity, are respectively mounted in the upper and lower cross-bars or standards 74^b and 74^c of the frame. The gear-wheel 75^b then is provided in its inner side with two concentric cam-grooves 76 and 77 of circular form except at one point, where their walls are deflected to form projections 76^a and 77^a, respectively, said projections being in line with each other and the groove 76 being widest adjacent to its projection. Mounted upon the cross-bar 74^d of the front or inner standard 74^c of the frame is a clamping-jaw 78, adapted to move horizontally toward and from a fixed jaw 79, also mounted upon said

cross-bar and provided with a rearwardly-projecting arm 80, carrying a friction-roller 81, which traverses the said cam-groove 76 in the gear 75^b. Arranged immediately below said jaws is a twister and cutter comprising a shaft or spindle 82, rotatably mounted in the said cross-bar 74^d and carrying at its front end a cutting-jaw 83, grooved on its inner face and provided at its rear edge with a cutting-blade 84 and at its rear end a pinion 84^a, which meshes with the gear 75^b. To this spindle is pivotally connected a complementary spindle 85, carrying at its inner end a jaw 86, ribbed on its inner face to tightly clamp the wires in the groove of the jaw 83 and normally held out of contact with said latter jaw by an interposed tension-spring 87. The twisting and cutting jaws are arranged in advance of the clamping-jaws and are somewhat longer than the same, so that the upper ends of the jaws of both sets have position in the same plane, and the upper ends of the jaws 79 and 83 are beveled off and made somewhat shorter than the jaws 78 and 86, so as to facilitate the feed of the binding-wires thereto. At its inner end said spindle 85 carries a friction-roller 88, which is adapted to traverse the wall of a groove 89, formed in the cross-bar 74^d of the intermediate standard 74^b of the frame. Opening through the wall of the groove at one point in the circumference thereof is a horizontal slot 90, in which a bearing-block 91 is arranged to slide, said block being normally pressed toward the groove 89 by a spring 92 and provided with a segment-shaped outer face 93, which when the block is in its normal position completes the circular formation of the wall of said groove 89. To the bearing-block is connected a reciprocating retractor 94, which carries a pin or roller 95, projecting into the groove 77 of the gear-wheel 75^b.

From the above description of the construction and arrangement of the parts it will be apparent that as the gear-wheel 75^b revolves in the direction of the arrow, Fig. 12, the pivoted jaws of the clamp and twister, which normally stand open in vertical position, will be closed against the fixed jaws by reason of the roller 81 traversing the narrow portion of the slot 76 and the roller 88 the walls of the groove 89, thus connecting said jaws and their spindles 82 and 85, so that they will rotate in unison. When the roller 81 on the jaw 78 and the pin 95 on the retractor 94, however, reach the projections at the deflected portions of grooves 76 and 77 in gear 75^b, the jaw 78 will be forced open by the projection 76^a and the retractor 94 moved outwardly by the projection engaging its pin 95, whereupon the bearing-block 91 will be retracted against the tension of its spring 92, and the spring 87 will force the jaw 86 open, and the roller on the spindle 85 thereof will occupy the open end of the slot 90 vacated by said block, as shown in Figs. 12 and 16. The jaws will then stand open

ready to receive the wires, and when said jaws are again operated in the manner above described the clamping-jaws 78 and 79 will engage the wire in rear of the twisting-jaws 83 and 86 and hold the same while the threading-needles are retracted to stretch the wires for the succeeding bale, and simultaneously therewith the latter jaws will be rapidly rotated to twist and cut the wires. The corresponding sets of devices which cut and twist the ends of the lower binding-wires are, as before stated, similarly constructed, but mounted upon the cross-bars 74^a of the standards 74^b and 74^c. Each gear-wheel 75^b and 75^c is provided in its outer side with a recess or depression 96, which is engaged by a spring-pressed detent-roller 97 on the frame to quickly arrest the motion of said wheels when the jaws are opened by the projections of the cam-grooves therein. By this means the parts are always maintained in their normal operative positions and all liability of the jaws being closed on account of the gear-wheels turning beyond the proper point by momentum obviated.

The construction and mode of operation of the several coacting elements of the machine having been described, the manner in which the binding-wires are threaded and tied will now be briefly set forth. Preliminarily the ends of the wires 72 are threaded through the eyes 42 in the needle 41 and bent back to form trailing portions 98, which are somewhat shorter than the distance between the clamping-jaws 78 79 and cutting and twisting jaws 83 86. When the threder is moved across the mouth of the baling-chamber, the trailing portion of each wire is carried past the twisting-jaws, but deposited in the clamping-jaws, as shown in Fig. 17, which close and clamp it. The needle is then retracted and the wire stretched thereby across the mouth of the baling-chamber is forced back by the straw into said chamber in the form of a loop 73, which embraces the sides and outer end of the bale, the wire unwinding from the reel and passing freely through the eye of the needle. During this operation the clamping-jaws 78 79 again open and the intermediate portion of the wire is drawn back between the cutting and twisting jaws 83 86 and under the upturned end of one of the clamping-arms—the arm 67, for instance—which opposes a frictional resistance to the release of the trailing portion 98. After sufficient straw has been compressed to form a bale the needle is again operated to stretch the wire across the inner end of the bale and complete the formation of the binding-loop, the end 100 being deposited between both sets of jaws 78 79 and 83 86 and clamped by the clamping-iron 67. The jaws then close about the portions 99 100 of the wires and firmly clamp them while the needle is being retracted, and the jaws 83 86 are rotated to twist and cut said portions of the wires, as shown in Fig.

20, the several ends of the feed-wire being held by the jaws 78 79, while the needle is moving back to stretch the wire across the mouth of the baling-chamber for the succeeding bale. This operation is illustrated in full in Fig. 21. While the above explanation in the main applies to a single binding-wire—the upper one—it will of course be understood that the operation of threading the lower wire 75 is the same, said lower wire being, however, engaged by the lower sets of clamping and twisting jaws and lower clamping-arm 70.

It will be obvious that the construction and arrangement of the parts of the machine may be varied to a considerable extent without departing from the spirit or sacrificing any of the advantages of the invention.

Having thus described the invention, what is claimed as new is—

1. In a baling-machine of the character described, the combination with a power-shaft carrying a feeder for automatically conveying the material to the compression-chamber, of a side shaft in gear with said power-shaft, a packing device mounted on a shaft driven from the side shaft, a needle-frame adapted to thread the binding-wires across the mouth of the compression-chamber and mounted on a crank-shaft independent of the side shaft 95 and carrying a gear arranged immediately below the same, a rotating segment mounted loosely on the side shaft and adapted when operated to mesh with the gear on the crank-shaft and thereby actuate the needle-frame, 100 a clutch device for rigidly connecting the said segment to the side shaft, a trip device for throwing said clutch into action, and a trip-wheel adapted to be turned by the material being compressed and carrying a striker to 105 operate said trip device, substantially as described.

2. In a baling-machine of the character described, the combination with a power-shaft carrying a feeder for automatically conveying 110 the material to the compression-chamber, of a side shaft driven from the power-shaft, a packing device mounted on a shaft in gear with the side shaft, a needle-frame for feeding the binding-wires across the mouth of the 115 compression-chamber, a shaft for operating said needle-frame independent of the side shaft and carrying a gear arranged immediately below the same, a transverse shaft provided at its end adjacent to the side shaft 120 with a gear, wire cutting and twisting mechanism operated from said transverse shaft, a counter-shaft provided at the inner end with a gear meshing with said gear on the transverse shaft and provided at its outer end with 125 a gear arranged on the inner side of the side shaft, a rotating segment mounted loosely on the side shaft and adapted when turned to mesh with the latter gear on the counter-shaft and the gear on the crank-shaft of the 130 needle-frame, trip mechanism for throwing said clutch device into operation, and a trip-

wheel adapted to be operated by the material being compressed and provided with a striker for actuating said trip mechanism.

3. In a baling-machine of the character described, the combination with a compression-chamber, and a feed chamber or hopper in communication therewith, of a power-shaft having a cranked portion, an oscillatory guide-block at the rear of the hopper, and a feed-fork having a head loosely mounted on the cranked portion of the shaft and provided at its lower end with tines and at its upper end with an arm moving loosely in an opening in said oscillatory block, substantially as described.

4. In a baling-machine of the character described, the combination with a feeder for automatically conveying the material to the compression-chamber, of a packer for forcing the material into the chamber, comprising a longitudinally-reciprocating carrier and an arm adapted to reciprocate transversely thereto and carrying a packing-finger, substantially as described.

5. In a baling-machine of the character described, the combination with a feeder for automatically conveying the material to the compression-chamber, of a packer comprising a carrier arranged to reciprocate in guides longitudinally of said chamber, a pivoted arm carrying a packing-finger adapted to reciprocate transversely in the mouth of said chamber, a pivoted connecting rod or arm jointed to the first-named arm, and a crank-shaft to which the latter arm is connected, substantially as described.

6. In a baling-machine of the character described, the combination with a power-shaft carrying a feeder for automatically conveying the material to the mouth of the compression-chamber, of a shaft in gear therewith, and driven thereby, a crank-shaft in gear with the latter shaft, and a packer comprising a carrier arranged to reciprocate in guides longitudinally of the compression-chamber, an arm pivoted thereto adjacent to its inner end and carrying at its outer end a packing-finger adapted to reciprocate transversely in the mouth of the compression-chamber, and a pivoted rod or arm jointed at its inner end to the packing-arm and connected at its outer end to the crank-shaft, substantially as described.

7. In a machine of the character described, the combination with a power-shaft, a feeder, and a shaft driven from the power-shaft, of a crank-shaft arranged immediately below the driven shaft and carrying at its upper end a pinion, a pivoted needle-frame connected with the crank-shaft and carrying needles for threading the binding-wires across the mouth of the compression-chamber, a segment loosely mounted on the driven shaft and adapted when moved to mesh with said pinion, a clutch-head rigidly mounted on said shaft and to which the segment is loosely connected, a pawl on the segment adapted to engage the

clutch-head, and means for periodically throwing the pawl into engagement with the head, substantially as described.

8. In a baling-machine of the character described, the combination of a frame having a compression-chamber and a hopper in communication therewith, a power-shaft carrying a feeder, a side shaft in gear with the power-shaft, a packer operated continuously from the side shaft, a crank-shaft independent of the side shaft and carrying a pinion, a pivoted needle-frame operated by the crank-shaft, cutting and twisting mechanism, clamping mechanism on the adjacent side of the frame of the machine for holding the wires while they are being twisted, a transverse shaft operatively connected with both the cutting and twisting and clamping mechanism, and carrying at its inner end a pinion, a counter-shaft provided at its forward end with a pinion meshing with the pinion on the transverse shaft and at its rear end with a pinion arranged adjacent to the pinion on the crank-shaft, a clutch-head on the side shaft, a rotating segment loosely mounted on the clutch-head and adapted to mesh with the two last-named pinions, said segment being provided with a spring-pressed pawl to engage the clutch-head, a trip-lever to hold the pawl out of engagement with the clutch-head and means for retracting the lever, substantially as described.

9. In a baling-machine, the combination with a feeder for automatically conveying the material to the compression-chamber, of a needle-frame carrying needles for feeding the upper and lower binding-wires across the mouth of said chamber, upper and lower duplicate sets of devices for receiving, twisting and severing the binding-wires, intermeshing cam-gears for operating said devices, an intermittent mechanism driven from the power-gearing of the machine for synchronously operating said needle-frame and cam-gears, substantially as described.

10. In a baling-machine of the character described, the combination with a feeder for automatically conveying the material to the compression-chamber, of a device for stretching the binding-wires across the mouth of the baling-chamber, and a twister coacting therewith comprising a pair of rotary twisting-jaws, one of which is pivoted and movable toward the other, a slidable block for closing the pivoted jaw, and a cam-wheel for operating said slidable block and rotating said jaws.

11. In a baling-machine of the character described, the combination with a feeder for automatically conveying the material to the compression-chamber, of a device for stretching the binding-wires across the mouth of the baling-chamber, and wire clamping, twisting and severing mechanism comprising a pair of clamping-jaws one of which is pivoted and movable toward the other, a pair of rotary cutting and twisting jaws arranged in ad-

vance of said clamping-jaws, one of the twisting-jaws being pivoted to move toward and from the other, means for closing the pivoted twisting-jaw, and a cam-wheel for closing the pivoted clamping-jaw, operating the said closing means and rotating the twisting-jaws.

12. In a baling-machine of the character described, the combination with a feeder for conveying the material to the compression-chamber, of a needle-frame arranged on one side of the chamber and having a pair of needles and adapted to move across the mouth of said chamber to stretch the upper and lower binding-wires, and wire clamping, twisting and severing mechanism on the opposite side of said chamber, comprising upper and lower duplicate sets of devices, each consisting of a pair of clamping-jaws one of which is pivoted and movable toward the other, a pair of rotary twisting-jaws one of which is fixed and carries a cutter and the other pivoted so as to move toward and from said fixed jaw, a spring normally holding said pivoted jaws open, a slidable member for closing the pivoted twisting-jaw against the tension of its spring, and intermeshing cam-wheels for synchronously operating said slidable member, closing the pivoted clamping-jaw against the tension of its spring and rotating the twisting-jaws, substantially as described.

13. In a baling-machine of the character described, the combination of a power-shaft carrying a feeder for automatically conveying the material to the compression-chamber, a side shaft in gear with the power-shaft, a crank-shaft carrying at its upper end a pinion arranged in proximity to the side shaft, a pivoted needle-frame connected to said crank-shaft and carrying needles to thread the binding-wires across the mouth of the compression-chamber, a segment loosely mounted on the side shaft and adapted when moved to mesh with said pinion, a clutch for rigidly connecting the segment to the shaft, and means for intermittently throwing said clutch into action, substantially as described.

14. In a baling-machine of the character described, the combination of a power-shaft carrying a feeder for automatically conveying the material to the compression-chamber, a side shaft in gear with the power-shaft, a crank-shaft carrying at one end a pinion arranged in proximity to the side shaft, a pivoted needle-frame connected to said crank-shaft and carrying needles to thread the binding-wires across the mouth of the compression-chamber, a toothed segment loosely mounted on the side shaft and adapted when moved to mesh with the said pinion, clutch mechanism for rigidly connecting the segment to the shaft, a trip-lever for normally holding the clutch retracted, a spring for throwing the clutch into action, and a trip-wheel operated by the material being compressed for retracting said trip-lever, substantially as described.

15. In a baling-machine of the character de-

scribed the combination, with mechanism for threading the binding-wires and mechanism for tying and severing the same, of a power-shaft, a side shaft in gear therewith, an intermittently-operated device having a clutch connection with the side shaft and adapted when operated to simultaneously actuate said two sets of mechanism, a movable trip-arm serving to hold the clutch connection out of engagement, and a trip-wheel adapted to be turned by the material under compression and carrying a striker for moving said arm to throw the clutch connection into engagement.

16. In a baling-machine of the character described, the combination with a feeder for automatically conveying the material to the compression-chamber, of a device for stretching the binding-wires across the mouth of said compression-chamber, and a twister coacting therewith and comprising a pair of rotary twisting-jaws one of which is movable toward and from the other, means for closing said movable jaw, a cam for operating said closing means, and means for rotating said jaws at the proper intervals.

17. In a baling-machine of the character described, the combination of a feeder for automatically conveying the material to the compression-chamber, of a device for stretching the binding-wires across the mouth of the chamber, wire clamping, twisting and severing mechanism comprising a pair of clamping-jaws one of which is pivoted and movable toward and from the other, a pair of rotary cutting and twisting jaws arranged in advance of said clamping-jaws, one of the twisting-jaws being movable toward and from its fellow jaw, and intermittently-actuated mechanism for closing the movable twisting and clamping jaws and rotating said twisting-jaws.

18. In a baling-machine of the character described, the combination with a feeder for automatically conveying the material to the compression-chamber, of a device for stretching the binding-wires across the mouth of the baling-chamber and a twister coacting therewith and comprising a pair of rotary twisting-jaws one of which is movable toward and from the other, a slidable block for closing the movable jaw, a reciprocating retractor for opening the same, and a cam-wheel for operating said retractor and rotating the jaws at the proper intervals.

19. In a baling-machine of the character described, the combination with a feeder for automatically conveying the material to the compression-chamber, of a needle-frame carrying needles for stretching the binding-wires across the mouth of said chamber, a pair of wire-clamping jaws one of which is movable toward and from the other, said jaws being arranged slightly below the plane of travel of the needle, a pair of rotary twisting-jaws arranged below and in advance of the clamping-jaws, one of said twisting-jaws being also movable toward and from its fellow jaw, and

means for closing said movable jaws and simultaneously rotating both of said twisting-jaws.

20. In a baling-machine, the combination 5 with a feeder for automatically conveying the material to the compression-chamber, of a needle-frame pivoted at one end upon one side of said chamber and carrying at its free end right-angularly-disposed needles having 10 eyes for reception of the wires and adapted when said frame is swung inwardly to thread the wires across the mouth of the chamber to the opposite side thereof, a shaft having

15 crank portions slidably connected to the needle-frame and carrying a pinion, an intermittently-operated segment meshing with the pinion, and means set into operation by the material being compressed for actuating said segment.

In testimony whereof we affix our signatures in presence of two witnesses.

SAMUEL RANKIN.
